The ornamental design for a filler spout, as shown and described.

DESCRIPTION

FIG. 1 is a top front perspective view of a filler spout showing my new design;

FIG. 2 is another top front perspective view thereof;

FIG. 3 is a front elevational view thereof;

FIG. 4 is a bottom plan view thereof;

FIG. 5 is a right side elevational view thereof, the left side being a mirror image of the right side;

FIG. 6 is a rear elevational view thereof; and,

FIG. 7 is a top plan view thereof.

The broken line representation of an inlet opening in FIG. 6, outlet openings in FIGS. 3 and 4 and the fragmentary broken line representation of a bathtub in FIG. 2 is for purposes of illustration only and forms no part of the claimed design.
